GATE LATCH

Filed Dec. 28, 1926

Herbert Wilburn
Inventor

UNITED STATES PATENT OFFICE.

HERBERT WILBURN, OF OTWAY, OHIO.

GATE LATCH.

Application filed December 28, 1926. Serial No. 157,532.

The present invention is an improvement in latch mechanisms and relates more especially to automatic fastening devices for gates and the like.

5 A further object of the invention is the provision of a latch mechanism which may be conveniently operated to release the gate when desired.

A still further object of the invention is 10 the provision of a latch structure which is of exceedingly simple design, durable, and efficient in operation.

Still another object of the invention is the 15 provision of a latch mechanism which can be manufactured at a relatively low cost and readily installed upon the standard forms of gate structures.

Other objects and advantages of the invention will become apparent as the description 20 progresses.

In the accompanying drawings forming a part of this specification and in which like reference characters are employed to designate corresponding parts throughout the 25 same:

Figure 1 is a top plan view of my improved latch mechanism shown in operative position in association with a gate and fence post,

30 Figure 2 is a side elevational view of the same,

Figure 3 is an enlarged transverse sectional view on the line 3—3 of Figure 2,

35 Figure 4 is a perspective view of one of the latch elements, and

Figure 5 is a perspective view of a complementary latch element.

Referring to the drawings, wherein for the purpose of illustration is shown the preferred embodiment of my invention, the numeral 10 indicates a fragmentary portion of a common type of fence post normally arranged in a vertical position, and shown in association therewith is a vertical bar 11 forming the outer free end of a gate of the ordinary swinging kind.

The primary feature of my invention is the production of a latch mechanism which may be readily applied to a gate for automatically engaging a keeper 12 secured to the fence post 10 and comprising an attaching plate 13 with a pair of projecting lugs 14 beveled at one side as shown.

With particular reference to the construction of my improved latch mechanism, the 55 numeral 15 indicates the supporting bracket

element consisting of a longitudinal plate 16 curved transversely to conform to the curvature of the gate bar 11 and formed with apertures 17 by which it is secured to the gate. 60 The upper end of the bracket 15 is formed with laterally extending ears 18 having vertically elongated slots 19 formed therein, and the lower end is provided with a pair of angular bearing flanges 20 presenting forwardly extending horizontal bearing arms 21 formed with transversely aligned pintle openings 22. This bracket is firmly secured upon the gate by means of screws or bolts passed through the apertures 17 into the gate 70 bar.

A complementary latch element 23 is pivoted to the supporting bracket 15, this complementary element comprising a tongue 23 disposed outwardly from the bar at the end 75 of the gate. The tongue is in the form of an elongated plate 24 disposed in a vertical position and curved inwardly at its lower end from which project a pair of arcuate bearing arms having pintle apertures 26 at their 80 outer ends.

Rigidly secured adjacent the upper end of the tongue plate 24 and projecting laterally therefrom is a substantially U-shaped actuating frame 27, the transverse bar 28 of which 85 is apertured for connection with the plate or tongue while the parallel members present horizontal side arms 29. Secured to the outer ends of the arms 29 and projecting laterally therefrom are a pair of handles 30 arranged for convenient engagement in swinging the tongue on its pivotal connection.

The lower extremities of the bracket member 15 and tongue section 23 are pivotally connected by means of a transverse bearing pin 31 extending through the openings 22 and 26 in the latch elements and secured against transverse displacement. A coiled spring is wound about the bearing pin 31, as indicated at 32, the centre of the spring 32 being formed with a U-shaped projection 33 bearing against the curved plate of the bracket element while the ends are extended against the bearing arms 25 of the tongue and secured thereto. This spring is formed so 100 as to normally urge the tongue 23 to an outward position away from the supporting bracket on the gate bar.

In use, the latch mechanism is rigidly secured upon the end bar of a gate, as indicated 110 in Figures 1 and 2 with the side arms 29 of the tongue actuating frame 27 projecting

horizontally through the slots 19 formed in the bracket ears 18. The tongue 23 is resiliently urged away from the bracket plate 16 on the gate bar by the coiled spring at the 5 pivot end of said tongue, the outward movement being limited by the laterally projecting handle members 30 at the outer ends of the U-shaped operating member of said tongue. Thus it will be noted that the gate 10 may be automatically fastened by imparting a swinging movement thereto, causing the latch mechanism to automatically engage the lugs on the keeper member 12 attached to the gate post. The gate is hingedly supported in 15 the usual manner so as to normally swing past the keeper lugs 14, the spring actuated pivoted tongue being then forced inwardly towards the gate structure and abruptly released to engage the right angular edges of 20 the lugs. This will prevent the gate from swinging in return movement and maintain the same in fastened position until the tongue is disengaged from the lugs by swinging it inwardly toward the gate bar to clear the 25 lugs 14 on the gate post.

It is to be understood that the form of my invention herewith shown and described is to be taken as the preferred example of the same, and that various changes as to the 30 shape, size, and arrangement of parts may be resorted to without departing from the spirit of the invention or the scope of the subjoined claims.

Having thus described my invention, I 35 claim:

1. A latch for gates comprising a supporting bracket for attachment to the gate, a pair of apertured ears formed at the upper end of the bracket, a pair of bearing flanges 40 formed at the lower end of the bracket, a tongue formed with bearing arms at its lower end, means for pivotally connecting the said bearing arms and flanges for swinging connection of the tongue to the bracket, spring

means adapted to normally urge the tongue 45 to an outwardly projected position, and a frame rigidly secured adjacent the upper end of the tongue having side arms extending through the apertured ears formed on the supporting bracket and adapted to permit 50 swinging movement of the tongue against the action of the spring.

2. In combination with a fence post, a keeper secured to the fence post, and a gate supported for swinging movement adjacent 55 the fence post, a latch mechanism including a supporting bracket for attachment to the outer vertical rod of the gate, laterally projecting apertured ears formed at the upper end of the bracket, angular bearing flanges 60 formed at the lower end of the bracket, a tongue pivotally associated with the bracket and having a pair of bearing arms formed at the lower end thereof, a bearing pin extended through openings in the bearing arms and bearing flanges for pivotal connection of the parts, a coiled spring wound about the bearing pin and adapted to normally urge the tongue to an outwardly disposed position, an 65 actuating frame rigidly secured adjacent the upper end of the tongue and having arms extending through the openings formed in the bracket ears, and handles at the outer ends of the frame for limiting the outward movement of the tongue and permitting swinging 70 movement thereof against the action of the spring.

3. A latch for gates comprising a bracket for attachment to the gate, a pair of apertured ears formed at the upper end of the 80 bracket, a tongue pivoted at its lower end to the lower end of the bracket for swinging movement with respect thereto, and a pair of arms at the upper end of the tongue extending through the apertured ears of the bracket for 85 guiding said tongue and operating the same with relation to the bracket.

HERBERT WILBURN.
